UNITED STATES PATENT OFFICE.

EARL V. COULSTON, OF CLEVELAND, OHIO.

STOVE.

1,098,097.

Specification of Letters Patent. Patented May 26, 1914.

Application filed January 4, 1913. Serial No. 740,183.

To all whom it may concern:

Be it known that I, EARL V. COULSTON, a citizen of the United States, resident of Cleveland, county of Cuyahoga, and State of Ohio, have invented a new and useful Improvement in Stoves, of which the following is a specification, the principle of the invention being herein explained and the best mode in which I have contemplated applying that principle, so as to distinguish it from other inventions.

My invention relates to stoves and particularly to that class of stoves in which the oven is heated by means of products of combustion of gaseous fuel or by means of the radiated or convected heat derived from the combustion of coal such as are shown, described and claimed in my Patent No. 1,032,816 issued July 16, 1912.

The object of the invention is to automatically control communication between the interior of the oven and the exterior thereof.

My said invention consists of means hereinafter fully described and particularly set forth in the claims.

The annexed drawing and the following description set forth in detail certain means embodying my invention, the disclosed means, however, constituting but one of various mechanical forms in which the principle of the invention may be applied.

In said annexed drawings:—Figure 1 represents a fragmentary, transverse vertical section of a stove embodying my invention. Fig. 2 represents a longitudinal vertical section of such stove.

In the illustrated embodiment of my invention A represents the main outer frame of the stove and B the fire-box of the same located laterally of the oven C. Suitable provision is made for carrying the gases of combustion from the fire-box B around the oven and out of the usual outlet-flue or smoke-pipe D. By these means the oven may be heated by means of these gases in the usual manner.

As in the above patented device, in the front of the stove is located a chamber E in which is placed a gas burner E'. Covering this chamber and extending rearwardly of the bottom of the oven is the deflector F also as in said previously patented device, provided with the lateral and end outlets f, f' from which said gases may enter into the main portion of the interior of the oven. Near the bottom and in one side of the oven

walls is the usual outlet opening e which is connected with the outlet duct C' which leads in the usual or any suitable manner to the smoke pipe or outlet duct D. Located at the mouth of this duct however, is a valve or damper G, which is adapted to close by gravity and cover the mouth of the duct C' and interrupt communication between the latter and the oven. This valve has formed thereon a projection or extension g which lies in the path of an inclined plane f² suitably secured to the side of the deflector F. This plane is located in a position such that when the deflector is in its normal position within the oven the lug g will occupy a position such as to raise the valve or damper G and thus permit communication to be established between the interior of the oven and the duct C'. This is the position which the parts occupy when the combustion of gas is used for the purpose of heating the interior of the oven, the products of such combustion passing out through the duct C' as will be readily understood. When, however, it is not desired to use gas, but to use coal for the purpose of heating the oven, the deflector F is removed, whereupon the mouth of the duct C' becomes automatically closed, as a result of the dropping of the valve G, so that during the heating process, the heated air confined in the oven cannot escape therefrom as is the case in an ordinary stove. When the gas is in use the chamber E is preferably covered by means of a suitable plate (not shown).

By means of the above described construction it will be seen that the interior of the oven is automatically arranged to lend itself to the use of either coal or gas as a fuel, by the mere removing or replacing of the deflector F.

Having fully described my invention, what I claim and desire to secure by Letters Patent is:—

1. In a stove, the combination of an oven; a source of heated gas communicating therewith; a detached member adapted to be moved into or completely removed from the interior of said oven; an outlet-flue communicating with the latter; and means operated by said detached member for establishing or disestablishing such last-named communication.

2. In a stove, the combination of an oven; a source of heated gas communicating therewith; a member adapted to be moved into

or removed from said oven; an outlet-flue communicating with said oven; and means operated by said member for establishing or disestablishing such communication, the latter being established when said member is within said oven.

3. In a stove, the combination of an oven; a source of heated gas communicating therewith; an outlet-flue also communicating with said oven; a deflector for such gas removable from said oven; and a valve for interrupting communication through said flue; said deflector being adapted to automatically operate said valve to close or open as it is respectively removed or replaced in said oven.

4. In a stove, the combination of an oven; a source of heated gas communicating therewith; an outlet-flue also communicating with said oven; a deflector for such gas and removable from said oven; and a valve adapted to interrupt such communication

and to assume an interrupting position by gravity; said valve provided with a lug or extension projecting, when in said position, 25 into the path of movement of said deflector.

5. In a stove, the combination of an oven; a source of heated gas communicating therewith; an outlet-flue also communicating with said oven; a deflector for such gas and removable from said oven; and a valve adapted to interrupt such communication and to assume an interrupting position by gravity; said deflector being provided with an inclined surface, and said valve with a 30 lug or projection lying in the path of movement thereof.

Signed by me, this 2nd day of January, 1913.

EARL V. COULSTON.
